VENDING MACHINE

Walter A. Tratsch and William Patzer,
Chicago, Ill.

Application March 20, 1937, Serial No. 132,069

2 Claims. (Cl. 74—167)

This invention relates to vending machines, and more particularly to dispensing mechanism of general application and especially suited to the dispensation of packaged articles such as cigarettes, candy and the like, and the invention includes, among its important objects, mechanism having a plurality of shelves or traps pivotally mounted and held in horizontal article-sustaining position by individual latch means adapted to be tripped by coin-free mechanism, to permit a lowermost one of the shelves to fall or pivot from horizontal position and discharge the article into a chute.

A further object is the provision of a plurality of article-bearing shelves arranged in tiers and pivotally mounted for movement from latched horizontal position so as to permit the gravitating movement of the supported article toward a discharge chute, each of the shelves having individual latch means and each tier of shelves or platforms having a traveling latch-release mechanism movable successively upward into engagement with individual latch means to release the same for discharge of the merchandise.

Still another object is the provision of a device of the character described in which merchandise is supported on a plurality of traps or platforms, arranged in tiers one above another, and manually operable mechanism for successively releasing the lowermost ones of said traps or platforms to effect the gravitating movement and discharge of merchandise therefrom.

Other and more specific details of construction and novel aspects of the invention will appear as the following specification proceeds in view of the annexed drawings in which:

Fig. 1 is a perspective view of a merchandise vending machine embodying the invention;

Fig. 2 is an enlarged vertical side section along lines 2—2 of Fig. 1;

Fig. 3 is a fragmentary horizontal section partly in plan, taken along lines 3—3 of Fig. 2;

Figs. 4 and 5 are opposite elevational details of the traveling latch-release mechanism and respectively taken along lines 4—4 and 5—5 of Fig. 3;

Fig. 6 is a front elevation of the traveling latch mechanism and traps or shelves; while

Fig. 7 is a side elevation along lines 7—7 of Fig. 6.

A vending machine embodying a preferred form of the invention includes, as seen in Fig. 1, a cabinet 10 having a transparent front panel 12, a merchandise discharge bin 14, a plurality of

manually operable selecting levers 16, and a coin-free release device 18.

The merchandise storing means seen in Fig. 6 includes a plurality of traps or shelves 20 pivotally supported along one edge, as at 22, on upright frame members 24 and arranged one above another.

Disposed oppositely of the upright 24 is another upright frame member 26 (see also Figs. 3 and 4) on which are pivotally mounted, as at 28, a series of latch members 30 arranged one above another, and one of each of the same being positioned substantially opposite one of the shelves 20 in its horizontal position, each of these latch members having an extending nose part 32 which underlies its corresponding shelf or trap 20 and holds the same in horizontal position, so that articles of merchandise 21 (Fig. 6) may be supported one above another upon these traps or shelves.

In Figs. 4 and 5 it will be observed that in a preferred arrangement of the invention, the upright frame members 24 and 26 may be in the form of channel members, and each of the trap latches 30 is provided with a laterally extending ear 34 which extends through an arcuate slot 36 in the upright 26 and into the channeled part thereof (Fig. 5) for engagement with one end of a coil spring 38 which is anchored at its other end 40 to the bottom of the channel part of the upright. By this means the latches are severally pivoted with their nose portions 32 extending in a lateral direction from the upright 26 toward their respective traps or shelves 20 (see also Fig. 7).

Positioned at one (left) side of the upright 26, as seen in Fig. 6, are two substantially flat upright ratchet rods or members 42 and 44. The former, termed for convenience the driving rod, is reciprocally movable by virtue of its support which includes a pair of spaced headed pins 46 and 46' extended into the main supporting structure, which are received in elongated slots 47 and 47' in the rod 42 and permit movement of the latter in a longitudinal direction against the tension of a normal positioning spring 48 (Figs. 2 and 6), one end of which is anchored to the frame structure, as at 49, and the other end of which is anchored to a lateral pin 50 on the rod 42.

This drive rod 42 is provided with a series of 50 edgewise ratchet teeth or notches 52 spaced apart therealong in positions opposite to corresponding ratchet teeth 54 in the stationary rod 44.

A traveling release mechanism is provided in the form of a plate 56 (Fig. 4) having a side 55

edge portion upset to form a cam and guide flange 58 having at one uppermost extremity a cam edge 59. The base plate 56 has an adjoining edge portion upset to provide a lateral plate 60 (Fig. 3), 5 in which are formed slots 61 and 62, respectively receiving the spaced rods 42 and 44, which arrangement, in conjunction with the disposition of the sidewise guide edge 58 which overlies the outer bottom surface of the channelled upright 10 26, serves to guide the plate structure 56 for slideable movement up and down the pair of rods 42 and 44, a presser spring 64 being extended from the plate 56 and adapted to ride on a side of the upright 26 to assure smooth operation of this 15 traveling latch rider.

Each of the latch members 30 is provided with a cam nose 33 normally disposed by means of its respective spring 38 in the path of movement of the cam edge 59 on the rider plate 56—58 as 20 the latter moves in its upward course on the upright 26, thus effecting a pivotatation of the several latches 30 out of latching position (i. e., clockwise in Fig. 4) as the rider moves past the same, thus releasing the corresponding trap or 25 shelf 20 from raised position.

Mounted on the plate 56 of the rider are twin dogs 66 (Figs. 6 and 7) each having offset nose portions 65 positioned for movement into the ratchet notches 52—54 in rods 42 and 44, such 30 movement being effected by means of twin spring members 67 bearing against the dogs and mounted on a common pivot 68 which is supported between a pair of ears 69 struck-up from the plate 56.

Tripping means for the twin dogs 66 is provided in the form of a lever 70 pivoted, as at 71, on a lug 72 extended from the base plate 56, this lever 70 having at one extremity a lateral arm 73 which extends beneath each of the dogs 66 35 and is adapted to bear against the same to raise them out of engagement with the latch rods 42 and 44 when this lever 70 is depressed by manual engagement with a handle portion 74 formed at its opposite extremity. When thus released, the 40 dogs 66 free the traveler 56 for movement up or down on the rods 42—44.

The drive rod 42 is reciprocated by means of a manually operated lever 16 (Fig. 2) pivoted on a suitable support, as at 17, within the cabinet 50 10, and having at its inner extremity an enlarged end portion with an opening 19 therein, desirably in the form of a parallelogram. At its lowermost extremity, the drive rod 42 is provided with a laterally extending pin 43 which is 55 disposed in the lever opening 19 in such manner that when the lever 16 is depressed the inner end portion thereof engages the pin 43 and urges the rod 42 upwardly and by virtue of engagement with the left-hand dog 66 urges the rider 56 a 60 distance equivalent to that between two adjacent teeth 52, the other (right-hand) dog 66 of the pair preventing retrograde movement. In this manner the rider 56 may be moved step by step from a lowered position to the uppermost 65 end of the rods 42—44, successively releasing the traps or platforms 20 as it does so.

As heretofore stated, the several selecting levers 16 are desirably coin-controlled, and in the present embodiment (Fig. 2) I have shown a 70 coin chute 18' schematically indicating an arrangement for depositing the coin in a control mechanism associated with the selecting levers 16, to free the same for movement in the manner described above, any suitable type of coin-control being used for this purpose, one such 75

mechanism especially designed for use with the present dispensing mechanism being shown in our co-pending application Serial No. 132,070, filed March 20, 1937.

Below the lowermost shelf of each group is a trap- or shelf-setting lever 80 (Figs. 2 and 6) in the form of a wire having a handle loop 81 at one extremity and passed through an opening in the upright frame member 24 immediately below the hinge or pivot 22 of the lowermost shelf, the innermost end portion 82 of this setting lever being bent back in a somewhat U-shape to underlie the lowermost shelf and being engageable with the same in its released or depending position to pivot the shelf into raised and latched position.

An examination of Fig. 6 illustrates in dotted lines a plurality of shelves or traps 20 in lowered position, and it will be apparent that when the lowermost shelf is raised by the lever 80 the 20 overlying shelves will correspondingly be pivoted into partially raised position so that they may be easily engaged by the hand for further movement into completely latched or raised position.

Operation

In summary, and with convenient reference between the several figures, the device is first charged with merchandise by pivoting the resetting handle 86 to raise the lowermost shelf into 30 latched, horizontal position and thereafter manually setting the overlying shelves in the manner just described, an article of merchandise 21 being placed upon each of these shelves. Previously, latch rider 56 will have been lowered into 35 initial position by depressing the lever 70 and raising the twin dogs 66 out of engagement with the ratchet notches 52—54 in rods 42—44 so as to avoid tripping the latches after the shelves are positioned.

In this condition the apparatus is ready for operation by deposit of a coin and manipulation of the coin control 18 which will free the levers 16 for manual operation, only one such lever being freed, however, when the type of coin control apparatus referred to in the above-mentioned application is employed, so that upon the depression of one of the levers 16 against the tension of its normal positioning spring 17' (Fig. 2), the movable drive or ratchet rod 42 will be 50 shifted upwardly to move the rider 56 upwardly to the adjoining notch.

During this upward movement of the cam edge 59 on the upset edge portion 58 of the rider will engage the nose 33 of one of the latched members 30 and pivot the latter out of latching position, thus permitting the shelf supported thereby to drop and discharge its merchandise into a 55 discharge chute 14' (Fig. 2) for gravitating movement into the bin 14.

The foregoing cycle of operation may be repeated by successive operation of the coin control and one of the selecting levers 16, until the rider shall have been moved upwardly past each of the pivoted latches 30 and until the 60 uppermost one of the tier of traps or shelves is released and the machine thus emptied of merchandise.

Various modifications and re-arrangements of the structure described herein to illustrate a preferred form of the invention will occur to those skilled in the art, and it is to be understood that our intention is to include all such variations and modifications within the scope of the appended claims.

Having thus described our invention, what we claim as new and desire to protect by Letters Patent is:

1. In a device of the class described, operating mechanism including a pair of bars having ratchet means thereon, said bars being supported in side by side relation, one of the same being reciprocable, a channel member adjacent said bars and extending collaterally therewith, a rider supported for reciprocable sliding movement by said bars and channel member, ratchet mechanism on said rider and cooperable with said ratchet means on said bars when the said one of the bars is reciprocated, to advance said rider in steps in a particular direction, releasable supporting dogs pivotally arranged in a series along the bottom of said channel member, said rider having a lateral hooked extension engaged around said channel member so as to move over said bottom thereof to successively engage said dogs and release the same one by one when the rider is advanced as aforesaid, and means for releasing said ratchet mechanism to permit restorative movement of said rider oppositely to said advancing direction.
2. In a vending machine, operating mecha-

nism including a pair of uprights arranged side by side in substantially parallel planes, ratchet means on said uprights, one of said uprights being reciprocable, a channel member extended collaterally of said uprights and having its channel bottom disposed in a plane substantially parallel to the planes of said uprights, a plurality of releasable supporting dogs arranged in a series along said bottom of the channel, a riding member supported for sliding movement by said uprights and channel in the direction of their length, said riding member having a portion arranged to move closely along said bottom of the channel member to engage and release said dogs, pawl mechanism coacting with said ratchet means and riding member and operable to effect step by step movement of the riding member in a particular direction upon reciprocation of the aforesaid reciprocable one of the uprights, and means on said riding member and operable to move said pawl mechanism into ineffective position so that the riding member may be moved at will relative to the uprights.
